UNITED STATES PATENT OFFICE.

GARFIELD P. SMITH, OF PROVINCETOWN, MASSACHUSETTS.

STAGE APPLIANCE.

1,330,452.

Specification of Letters Patent. Patented Feb. 10, 1920.

Application filed June 28, 1919. Serial No. 307,327.

To all whom it may concern:

Be it known that I, GARFIELD PERRY SMITH, a citizen of the United States, residing at Provincetown, in the county of Barnstable and State of Massachusetts, have invented 5 certain new and useful Improvements in Stage Appliances, of which the following is a specification.

The invention relates to an improvement 10 in stage appliances, and particularly to an apparatus for instructing the public in the operation and manner of discharging torpedoes, mines, and other objects from submarine boats, and demonstrating the possibility 15 of escape from a submerged craft in the event of the failure of the resources commonly employed on this class of boats for giving them sufficient buoyancy to bring them to the surface. While various constructions 20 of minute details are omitted, the details of the actual operation of discharging a torpedo or other object from a boat is portrayed, it of course, being understood that such details are omitted for simplifying 25 the illustration and that various modifications are incorporated in order to show, in the simplest manner, the actual operation of such apparatus.

In carrying out my invention, I purpose to 30 install a tank adapted to contain a quantity of water, and to connect to the tank a cylindrical tube to simulate a torpedo tube, and to provide the said tube with inboard and outboard covers or closures, and to provide 35 means for operating them in substantially the same manner as in actual applications of submarine boats.

The invention comprises certain new and 40 novel features, combinations and arrangements of construction as will be hereinafter fully described and claimed.

In the drawings, illustrating the invention, in the several figures of which like parts are similarly designated, Figure 1, is a 45 face view of the apparatus embodying my invention. Fig. 2, is a transverse section of the same drawn on the line 2—2 of Fig. 1, parts being broken away. Fig. 3, is a transverse section drawn on the line 3—3 of 50 Fig. 1. Fig. 4, is a detail of construction.

In the drawings I do not purpose to dwell 55 upon the details of construction of the tank employed in my apparatus, nor upon the details of filling and drawing off the water from the tank since such details are obviously well known and understood by those

conversant in the art of stage appliances wherein tanks are employed for various aquatic demonstrations.

1 designates a tank having a glass front 2, 60 and at one end of the tank 1 there is projected, what might be called, the outer end of a cylindrical tube 3, the said tube having a cover 4 associated with the outer end thereof and a cover 6' for closing the inner end 65 thereof. The cover 4 is operated from the exterior of the tank by means of a shaft 5 and suitably mounted gears 6, simulating those of the construction of a ship. The inner end of the tube, or what is commonly 70 referred to as the inboard end is provided with a cover 6', adapted to be closed water tight upon the inner end of the tube when the opposite end is open, whereby to permit the discharge of an object from the tube as 75 will be hereinafter described.

Any suitable means may be employed for closing the outer cover of the tube air and water tight so as to prevent escape of water from the tank and from the tube when the latter is being "loaded". In practice I 80 purpose to arrange glass panels 7 in the sides of the tube 3 so as to permit the audience to observe the actual operation of the expulsion of an object from the tube. 85

I have not attempted to go into minor details of the construction of my appliance as I acknowledge that various details may be installed without departing from the broad idea of my invention and therefore have not considered it incumbent to dwell in detail on the construction of parts as may readily present themselves to a mechanic of ordinary skill. 90

9 designates an air inlet pipe extending 95 from a suitable source of compressed air supply (not shown) located in convenient relation to the tube, the said pipe having a valve 10 for controlling the admission of air to the tube to expel the torpedo or 100 other object demonstrating the invention. It will of course be appreciated that the air under pressure from the source of supply will be equal to that only of the external pressure exerted by the water in the tank, 105 so that, when air is admitted into the inner end of the tube the expulsive force will be sufficient only to drive the contents of the tube out into the tank without damage thereto. It will be further understood that 110 while my invention is designed to educate the public in the operation of the expulsion

of a torpedo, a mine, or other object from a submerged vessel it also is intended to educate the public toward the possibilities of safety of the crew of a boat.

5 I do not claim broadly the idea of a portable water tank adapted for stage appliances since I am fully aware that such devices have heretofore been employed but what I do claim as new and desire to secure 10 by Letters Patent is:—

1. In a stage appliance, a water containing tank provided with a transparent front, a tube connected with and extending into the tank through one end thereof, covers for the 15 ends of the tube for closing the ends air- and water-tight, means operable from without the tank for opening and closing said covers, and means for conducting an expelling medium to the inner end of the tube, 20 when the outer cover is open whereby to force the object from the tube into the water of the tank.

2. A stage appliance, a tank having a transparent front, a tube opening through 25 one end of the tank and having an inner and an outer water-tight closure for the respective ends thereof, means operable from the exterior of the tank for controlling the position of said outer cover and means for 30 admitting air under pressure to the inner end of the tube when the said outer cover is open.

3. A stage appliance, a water tank having a transparent front, a tube connected water-tight to one end of said tank below the water line thereof, a cover for the outer end of said tube, means operable from the exterior of the tank for controlling the position of said cover, a cover for the opposite end of tube, means for sealing the cover to said end of 40 said tube, and means for admitting air under pressure to the inner end of the tube, substantially as and for the purpose specified.

4. A stage appliance, comprising a water holding tank having a transparent front, a tube having its outer end opening through one end thereof and connected water-tight thereto, said tube having transparent panels arranged therein, closures for the inner and outer ends of said tube, means operable from the exterior of the tank for controlling the position of the outer cover of the tube, means for locking the inner closure of the tube and means for admitting air under 50 pressure to the inner end of the tube, as and for the purpose specified.

In testimony whereof I have hereunto set my hand this 24 day of June, 1919.

GARFIELD P. SMITH.
